UNITED STATES PATENT OFFICE

2,478,342

ANCHOR

Charles C. Thompson, McComb, Miss.

Application April 24, 1947, Serial No. 743,704

2 Claims. (Cl. 114—208)

1

My invention relates to anchors and in particular to anchors of the so-called non-fouling type.

It is an object of my invention to provide an improved non-fouling anchor construction.

It is another object to provide an improved anchor of extremely simple construction having particular application to the securing of small vessels.

It is a general object to provide a rugged, light, easily fabricated, and cheap non-fouling anchor.

Other objects and various further features of the invention will be pointed out or will occur to those skilled in the art from a reading of the following specification in conjunction with the accompanying drawings. In said drawings:

Fig. 1 is a top view of an anchor incorporating features of the invention; and

Fig. 2 is a sectional view of the anchor of Fig. 1, the section being taken along the line 2—2 of Fig. 1.

Briefly stated, my invention contemplates an anchor having a frame formed with bifurcated shank pivotally suspending a twin-bladed fluke from spaced points on said shank. In the form to be described, the frame is generally circularly formed as a loop of cylindrical stock and the fluke is suspended from generally diametrically spaced points on said loop. The fluke arms extend radially enough to intercept the shank, so that no matter which way the device may land on the bottom one of the fluke arms may engage the bottom and be locked against rotation by the action of the other fluke arm engaging the shank.

Referring to the drawings, my invention is shown in application to an anchor comprising a frame 5 in which fluke means 6 is pivotally suspended. The frame 5 includes a generally arcuately formed shank portion which in a single arcuate span may define two shank forks 7—8. The fluke means 6 is preferably suspended from widely spaced bearing portions 9—10 of the shank forks 7—8. In the form shown, the frame 5 is bent up from a single elongated piece of cylindrical stock, and the bending is such as to have the frame 5 generally circular. A cable ring 11 may be secured to the frame 5 between the shank forks 7—8; in the form shown the cable ring 11 is integrally formed of the same stock as the frame 5, as by a reverse twist, to produce an overall "figure-of-eight" structure. The loop defining the cable ring 11 may be of lesser radius than the loop defining the frame 5.

It is preferred that the ends of stock forming

2

the frame 5 terminate or abut each other at some point 12 away from the shank or towing end of the frame 5. In the form shown, this point 12 is generally opposite the cable ring 11 and intermediate the bearing portions 9—10 of the frame 5. If desired, the ends of the stock may be secured at 12, as by brazing or by a butt weld.

As indicated, for a non-fouling anchor the fluke means 6 preferably comprises two fluke arms 13—14, and in accordance with a feature of the invention these arms may be integrally formed from a single strap which is centrally bent. For more effective securing to the bottom, the tips 15—16 of the blades of the fluke means 6 may be pointed. The arms 13—14 of the fluke 6 may be pivotally suspended near the bend thereof, and in the form shown a shaft 17 effects this suspension. The shaft 17 may fit in the saddle between arms 13—14 and be secured thereto as by welds or brazing 18.

In accordance with a feature of the invention, the ends of the shaft 17 are formed with shoulders 19—20 defining projecting journals 21—22 to fit within bearing means in the portions 9—10 of the frame 5. If desired, to enhance the effectiveness of the bearing suspensions, the portions 9—10 may be more or less flattened from the bar stock of frame 5, so as to provide greater diametral support for the journals 21—22 of the fluke means. The preferred relation between the points of suspension for the fluke 6 and the length of fluke arms 13—14 is that the arms be long enough to intercept the shank 7—8. Since the shoulders 19—20 serve axially to locate the fluke 6, it may be said that in the form shown the distance between shoulders 19—20 is preferably less than the radial extent of fluke arms 13—14 from the axis of shaft 17.

It will be appreciated that I have described an extremely simple non-fouling anchor construction. The construction is not only simple to fabricate and assemble but also to carry and use. These features are obtained without sacrifice of effectiveness for the size and weight of anchor. The particular form described may be readily assembled as by spreading the bearing portions 9—10 slightly to admit first one journal, say 21, and then the other into its appropriate bearing.

While I have described my invention in detail for the preferred form shown, it will be understood that modifications may be made within the scope of the invention as defined in the appended claims.

I claim:

1. In an anchor, a frame comprising a single piece of bar stock formed into a cable loop and

into two arms diverging from said cable loop, said arms having aligned bearing openings, a pintle having its ends revolvably mounted in said bearing openings, fluke means rigid with and carried by said pintle and comprising a fluke at each side of said frame and of a length to contact said frame for stopping said fluke means for the purpose set forth.

2. In an anchor, a frame comprising a single piece of bar stock formed into a cable loop and into two arms diverging from said cable loop, fluke means pivotally mounted on and between said arms, said fluke means comprising a fluke at each side of said frame and of a length to contact said frame.

CHARLES C. THOMPSON.
